UNITED STATES PATENT OFFICE.

HENRY THOMAS KNIGHT, OF TORONTO, CANADA.

DEVICE FOR TYING BAGS.

SPECIFICATION forming part of Letters Patent No. 635,257, dated October 17, 1899.

Application filed April 28, 1899. Serial No. 714,905. (No model.)

To all whom it may concern:

Be it known that I, HENRY THOMAS KNIGHT, mechanic, of the city of Toronto, in the county of York, in the Province of Ontario, Canada, 5 have invented certain new and useful Improvements in Devices for Tying Bags; and I do hereby declare that the following is a full, clear, and exact description of the same.

My invention relates to improvements in 10 devices for tying bags in which semicircular sections of strong wire are employed, each piece linked to the other, the whole forming a ring designed to encircle the mouth of the bag; and the object of my invention is to 15 provide a durable, cheap, and thoroughly efficient tie for the purpose named. I attain these objects by the description illustrated in the accompanying drawings, in which—

Figure 1 shows a detail view of the tie 20 opened. Fig. 2 is a sectional view. Fig. 3 is the securing device. Fig. 4 is the lever attachment.

The body of the ring is composed of two 25 semicircular sections of wire of some strong material, the one end of each section being looped together. The object of looping them together is to allow of an easy opening operation. If it were one piece of circular wire, the continual opening of the ring would, I 30 claim, break the wire in the center. I therefore form the ring in two or more sections. On the one end of one of these sections is a closed loop. Into this loop is inserted a short 35 piece of wire suitably shaped, which I will term a "lever." The one end of this lever is looped into the loop of the semicircular section, the loops together being closed, thus securing the same to that end of what I will call the "ring." The opposite end of the 40 other semicircular section of the ring is provided with a hook-shaped end intended for the reception of the lever, which is securely attached to the other end of the ring. By bringing the lever into the hook-shaped end 45 it will be easily seen that when you draw on the lever it will bring the two semicircular sections together more easily than by simply drawing them together by hand. On the same loop end to which is attached the lever 50 I have provided a short hook, which I term the "securing device." The one end of this

device is looped securely into the loop of one of the semicircular sections. The other end of this device is hook-shaped and is designed to catch into the opposite hook-shaped end of the semicircular section into which the lever has already been shown to catch, so that when the two ends of the semicircular section are drawn together by the lever this securing device is hooked into the 60 hooked end of the semicircular section. Then the lever is released and the hooked securing device holds the semicircular section together, making a continuous ring in sections. The mouth of the bag gathered and this tie being 65 placed around, as described, makes a very secure and easily-operated tie and completely does away with string or any of the old and hard-to-operate methods already in use. The whole tie can be attached to the bag by 70 means of a clenched staple or can be sewed onto the bag and is always in place and ready to operate when desired.

In order that this description may be more easily understood, I invite attention to the 75 accompanying drawings, in which—

5 are the semicircular sections. These sections are linked together at 6. On the end 7 is a closed loop, into which is looped the lever 8 and also the securing device 9. On the 80 other end of the one semicircular section at 10 is the hook-shaped end for the reception of the lever 8 and also for the reception of the securing device 9. The securing device is hook-shaped at 11 and designed to catch into 85 the hook-shaped end 10, the lever 8 also being brought into the hook-shaped end 10 and designed to be drawn back to the end 7, thereby bringing the two ends 7 and 10 near enough together to allow the securing device 9 to 90 catch into the hooked end 10, then releasing the lever 8. The hook being caught makes a continuous tie or ring.

The advantage of my invention is principally its compactness, simplicity, and inexpensiveness and its thorough efficiency, producing a combination which is practical in every respect and will fill a long-felt want. 95

Having thus fully described my invention, what I claim as new, and desire to secure by 100 Letters Patent, is—

In a tie for bags, made of two semicircular

pieces of wire 5, 5, being linked together at the loops or eyes 6, one section having an eye or loop 7, a lever 8, with an eye or loop on one end secured to loop 7, a securing device 9, 5 also looped into 7, one end of securing device is hook-shaped at 11, the other semicircular portion having a hook 10, all these parts formed, combined and arranged in detail, whereby

they are adapted to encircle and receive the mouth of a bag, substantially as described. 10

Toronto, April 5, A. D. 1899.

HENRY THOMAS KNIGHT.

In presence of—
HECTOR MOWAT,
FRANCIS HORE.
